C. W. PALMER

PRODUCTION OF YARNS OR THREADS

Filed Aug. 4, 1924

FIG. 1.

FIG. 2.

INVENTOR

CHARLES W. PALMER,

By his Attorneys,

By his Attorneys,
Baldwin. Wright.

Patented June 5, 1928.

1,672,083

UNITED STATES PATENT OFFICE.

CHARLES WILFRED PALMER, OF SPONDON, NEAR DERBY, ENGLAND, ASSIGNOR TO
CELANESE CORPORATION OF AMERICA, A CORPORATION OF DELAWARE.

PRODUCTION OF YARNS OR THREADS.

Application filed August 4, 1924, Serial No. 729,999, and in Great Britain September 19, 1923.

This invention relates to a process and apparatus for the manufacture of compound yarns or threads consisting of or comprising so-called "dry-spun" artificial filaments or threads of cellulose acetate, nitrocellulose, ethyl-, methyl-, or benzyl cellulose or other esters, ethers or derivatives of cellulose, and of threads or yarns of cotton, linen, silk, spun silk, wool, artificial silk of the cellulose type or other textile fibres or filaments (hereinafter referred to as the other fibre or fibres) doubled or twisted together with said dry-spun artificial filaments or threads.

Dry-spun artificial filaments or threads, as is well known, are those which are produced by extrusion of solutions of the cellulose esters, ethers or derivatives in vaporizable solvents through fine orifices into an evaporative atmosphere, usually a current of heated air, the extrusion and formation of the filaments generally taking place in an enclosed metier, cabinet or casing.

Hitherto compound yarns or threads such as before referred to have been manufactured by separate and independent operations of the cellulose ester or derivative being dry-spun and wound, with or without twisting, and being subsequently rewound and then doubled or twisted on other machines with the other fibre or fibres to form the compound yarn or thread.

Now according to the present invention I combine the production of the filaments of cellulose ester, ether or derivative and the twisting or doubling thereof with the other fibre or fibres into one operation, by continuously associating the yarn or thread of the other fibre or fibres with the filaments of the cellulose ester, ether or derivative in the travel of the latter from the metier, cabinet or the like in which they are produced, twisting the associated filaments and yarn or thread together to form the compound yarn or thread and winding the compound yarn or thread as it is produced.

The twisting or doubling of such other fibre or fibres with dry-spun filaments of cellulose esters or ethers as a single operation continuously with their production may in particular be effected by means of cap spinning devices, and in this regard the invention may especially be applied in connection with a process or apparatus where in the filaments of the cellulose derivatives

formed by extrusion in an evaporative atmosphere are led on in association for threads and continuously cap spun by cap spinning devices, preferably situated outside the metier, cabinet or casing in which the filaments are produced. The twisting or doubling of the "dry-spun" filaments with the other fibre or fibres in one operation continuously with their production may, however, be effected by other means than cap spinning and the invention is applicable generally for employment in connection with processes wherein filaments of cellulose acetate, or other esters, ethers or derivatives of cellulose are produced by the dry spinning or evaporative method.

It is to be understood that the invention is not confined to the doubling or twisting of a single thread, yarn or "end" of a textile fibre or fibres with one "end" or thread of the dry-spun filaments, and that two or more "ends" of cotton yarn or other textile fibre or fibres may be associated with one or more "ends" of the dry-spun filaments and twisted together therewith continuously in their production.

Any suitable apparatus may be employed for the purpose of the invention, such apparatus comprising means for bringing one or more "ends", threads or yarns of the other fibre or fibres into association with one or more "ends" of the dry-spun filaments in the travel of the latter from the extrusion device, and means for twisting the associated filaments and fibres together and winding the resulting compound thread or yarn.

Preferably the said associating, twisting and winding devices are situated outside the metier, cabinet or casing in which the dry-spun filaments are produced, the filaments (associated together in any desired number for the given thread) being led out of the metier, cabinet or casing to the devices for associating them with the other fibre or fibres and for twisting and winding the compound thread or yarn.

The twisting of the dry-spun filaments with the associated yarns or threads of the other textile fibre or fibres may be in the same direction as the twist of the other textile fibre or fibres or in the opposite direction thereto. It is preferable however, especially in the case of employment of cotton yarns, for example two fold cotton twist

that the twisting of the compound yarn or thread shall be in the same direction as that of the yarn associated with the dry-spun filaments.

5 The invention can be applied with especial advantage for the production of compound yarns of dry-spun cellulose acetate filaments and cotton.

10 The accompanying drawings illustrate by way of example one form of apparatus constructed in accordance with the invention, shown as applied to a metier of the character described in the British specification of British Cellulose and Chemical Manufacturing Co. Ltd., and others, No. 198,023, wherein the dry-spun artificial filaments produced in the metier are led on in association for threads and continuously twisted and wound by cap spinning devices. The accompanying drawings show only so much of the metier and apparatus as is necessary to illustrate the present invention.

Fig. 1 is a diagrammatic front elevation of one form of apparatus used.

25 Fig. 2 is a diagrammatic side elevation of the apparatus with the metier casing in diagrammatic section.

The fascicles of filaments, formed by extrusion of a solution of cellulose acetate or 30 other cellulose derivative in a volatile solvent through nozzles or spinnerets 2, into a heated atmosphere in the metier casing 3, are led, each associated as a thread or "end" 35 1^a, out of the metier casing through small orifices 4, and each "end" of filaments 1^a passes forwardly over the drawing roller 5 back through a guide eye 6 where it is associated with the cotton or other yarn 10 to 40 form the compound thread before returning over the drawing roller 5 to the cap spinning mechanism. Above the drawing roller is mounted a creel frame 7 extending for the length of the latter and having pegs 8 to receive the bobbins 9, cheeses or the like 45 of cotton or other yarn to be associated with the respective filament threads or "ends" 1^a to form the compound yarn. The cotton or other yarn 10 for each compound thread is led down through a guide eye 11, round 50 under the drawing roller 5 and through the corresponding guide eye 6 for association with the thread 1^a of filaments, and each compound yarn 12 thus formed travels forwardly over the drawing roller 5 and a tension roller 13 to the thread guide or balloon guide 14 of the cap spinning device and thence under the edge of the cap 15 on to the bobbin 16 of the cap spinning device.

60 The drawing roller 5 is preferably driven at a higher surface speed than the rate of extrusion of the filaments so that the latter are drawn out in their travel to the drawing roller. The bobbins 16 are driven and traversed in the same manner as indicated 65 in the said British specification 198,023, and

it will be understood that the compound yarn 12 is simultaneously twisted and wound by the action of the cap spinning devices, the bobbins or winding members of which are driven at a much higher speed 70 than the rate of feed of the compound yarn.

It is to be understood that the apparatus described with reference to the drawings is given by way of example only and can be varied in wide limits within the spirit of 75 the invention. Also that instead of cap spinning devices other twisting and winding devices may be employed for the compound yarns or threads.

It will be seen that a great economy can 80 be effected by the present invention, in that a doubled or compound yarn of the character referred to can be produced in one process, whereas with previous methods it has been necessary to re-wind the dry-spun artificial silk and subsequently to twist it with 85 the other fibre or fibres.

Also the product is superior, in consequence of the reduced amount of handling involved. Moreover, by twisting the other 90 fibre or fibres in one operation continuously with the formation of the dry-spun artificial silk as described, a greater covering power can be obtained from the latter, in that it can be doubled and twisted with the other 95 fibre without there being any twist in its individual filaments, whereas when it is spun and twisted separately the individual filaments are twisted and have less covering power in the compound yarn.

100 What I claim and desire to secure by Letters Patent is:

1. A process for the simultaneous production of dry spun filaments and the manufacture of compound yarns composed of such 105 dry spun filaments of cellulose derivatives and of threads of other fibers which comprises forming dry spun filaments of cellulose derivatives in a metier casing, withdrawing these filaments directly from the 110 casing, feeding the threads of other fibres into intimate association with the filaments as the latter leave the casing, and continuously twisting and winding the travelling associated threads and filaments, thereby 115 forming a compound yarn.

2. A process for the simultaneous production of dry spun filaments and the manufacture of compound yarns composed of such dry spun filaments of cellulose derivatives 120 and of threads of other fibers which comprises forming dry spun filaments of cellulose derivatives in a metier casing, withdrawing these filaments from the casing, feeding threads of other fibres into association with the filaments as the latter leave the casing and before they have received any twist, and continuously cap spinning the travelling associated threads and filaments, thereby forming a compound yarn. 125

3. A process for the simultaneous production of dry spun filaments and the manufacture of compound yarns composed of such dry spun filaments of cellulose derivatives and of threads of other fibers which comprises forming dry spun filaments of cellulose acetate in a metier casing, withdrawing these filaments directly from the casing, feeding the threads of other fibres into intimate association with the filaments as the latter leave the casing, and continuously twisting and winding the travelling associated threads and filaments, thereby forming a compound yarn.
- 10 4. A process for the simultaneous production of dry spun filaments and the manufacture of compound yarns composed of such dry spun filaments of cellulose derivatives and of threads of other fibers which comprises forming dry spun filaments of cellulose acetate in a metier casing, withdrawing these filaments directly from the casing, feeding threads of other fibres into intimate association with the filaments as the latter leave the casing and before they have received any twist, and continuously cap spinning the travelling associated threads and filaments, thereby forming a compound yarn.
- 15 5. An apparatus for the simultaneous production of dry spun filaments and the manufacture of compound yarns composed of such dry spun filaments of cellulose derivatives and of threads of other fibers which comprises means for dry spinning filaments of cellulose derivatives in a metier casing, means for supplying threads of other fibres, 60 a drawing roller to which the filaments are fed directly from the casing, and the threads from the bobbins, means for associating the filaments and threads, and means for simultaneously twisting and winding the associated filaments and threads to form a compound yarn.
- 20 6. An apparatus for the simultaneous production of dry spun filaments and the manufacture of compound yarns composed of such dry spun filaments of cellulose derivatives and of threads of other fibers which comprises means for dry spinning filaments of cellulose acetate in a metier casing, withdrawing these filaments directly from the casing, feeding threads of other fibres into intimate association with the filaments as the latter leave the casing and before they have received any twist, and continuously cap spinning the travelling associated threads and filaments, thereby forming a compound yarn.
- 25 7. An apparatus for the simultaneous production of dry spun filaments and the manufacture of compound yarns composed of such dry spun filaments of cellulose derivatives and of threads of other fibers which comprises means for dry spinning filaments of cellulose derivatives in a metier casing, means for supplying threads of other fibres, 65 a drawing roller to which the filaments are fed directly from the casing and associating said threads therewith, and a cap spinning device for simultaneously twisting and winding the associated filaments and threads to form a compound yarn.
- 30 8. An apparatus for the simultaneous production of dry spun filaments and the manufacture of compound yarns composed of such dry spun filaments of cellulose derivatives and of threads of other fibers which comprises means for dry spinning filaments of cellulose derivatives in a metier casing, bobbins for supplying threads of other fibres, 70 a drawing roller to which the filaments are fed directly from the casing and the threads from the bobbins, means for associating the filaments and threads, and a cap spinning device for simultaneously twisting and winding the associated filaments and threads to form a compound yarn.
- 35 9. An apparatus for the simultaneous production of dry spun filaments and the manufacture of compound yarns composed of such dry spun filaments of cellulose derivatives and of threads of other fibers which comprises means for dry spinning filaments of cellulose derivatives in a metier casing, means for supplying threads of other fibres, 75 a drawing roller to which the filaments are fed directly from the casing and the threads from the bobbins, means for associating the filaments and threads, and a cap spinning device for simultaneously twisting and winding the associated filaments and threads to form a compound yarn.
- 40 10. An apparatus for the simultaneous production of dry spun filaments and the manufacture of compound yarns composed of such dry spun filaments of cellulose derivatives and of threads of other fibers which comprises means for dry spinning filaments of cellulose derivatives in a metier casing, means for supplying threads of other fibres, 80 a drawing roller to which the filaments are fed directly from the casing and the threads from the bobbins, means for associating the filaments and threads, and a cap spinning device for simultaneously twisting and winding the associated filaments and threads to form a compound yarn.
- 45 11. An apparatus for the simultaneous production of dry spun filaments and the manufacture of compound yarns composed of such dry spun filaments of cellulose derivatives and of threads of other fibers which comprises means for dry spinning filaments of cellulose derivatives in a metier casing, means for supplying threads of other fibres, 85 a drawing roller to which the filaments are fed directly from the casing and the threads from the bobbins, means for associating the filaments and threads, and a cap spinning device for simultaneously twisting and winding the associated filaments and threads to form a compound yarn.

In testimony whereof I have hereunto subscribed my name.

CHARLES WILFRED PALMER.
